UNITED STATES PATENT OFFICE.

MELVIN VANIMAN, OF GENEVILLIERS, FRANCE.

AEROPLANE.

No. 884,432.

Specification of Letters Patent. Patented April 14, 1908.

Application filed November 27, 1906. Serial No. 345,394.

To all whom it may concern:

Be it known that I, MELVIN VANIMAN, a citizen of the United States of America, and resident of Genevilliers, France, have invented a new and useful Improvement in Aeroplanes, which improvement is fully set forth in the following specification.

The present invention has for its object an aeroplane which is broadly characterized by the combination with an oblong horizontal plane, the edges of which are appropriately bent below the horizontal, in such a manner as to form a parachute, of a vertical plane dividing the volume of air into two equal volumes below the horizontal plane along the longitudinal axis of this latter. This aerial machine is driven by two screws arranged beneath the horizontal plane on each side, and at an equal distance from the median vertical plane.

In order to render the following explanations as clear as possible, the accompanying drawings show by way of example the aeroplane which forms the object of the invention.

Figure 1 is a longitudinal elevation of the apparatus. Fig. 2 is a cross-section on the line A—A of Fig. 1. Fig. 3 is a plan view. Fig. 4 is a cross-section on the line B—B of Fig. 1. Fig. 5 is an elevation of the front portion of the apparatus.

The horizontal plane *a* is constituted by an appropriate number of strips of silk fabric, sewed to a suitable frame formed by bamboo rods and aluminium tubes for the sake of lightness. The seams of the bands, which preferably run longitudinally, are each formed by a steel wire which, as will be understood, increases the strength of the fabric at the seam.

The plane *a* which is of oblong form, is bent below the horizontal towards its edges as represented in Figs. 2 and 4. In addition its front and rear extremities terminate in a part *b* or *b'*. This part *b* or *b'* is mounted upon a suitable frame of aluminium tubes and steel wires, and jointed to the plane *a* along *c c* as regards the part *b* and *c' c'* as regards the part *b'*.

The parts *b* and *b'* serve three purposes: 1. They form part of the plane *a* for supporting the whole of the system. 2. Being jointed, they serve to control the motion for the purpose of causing the apparatus to rise or fall or to drive it horizontally. 3. In case of accident to the motor, they may be

turned down vertically in such a manner as to form a parachute.

A longitudinal reinforced beam *d e f g*, Figs. 2 and 4, is adjacent to the horizontal plane *a*, and carries a platform *h*, Figs. 1 and 2. The parts *d e* and *d g* of this beam are covered with silk fabric, in such a manner as to protect them from the resistance of the air.

The parts *e f* and *f g* are likewise silk-covered; these coverings of the reinforced beam protect it from the resistance of the air, and divide the surface constituting a parachute *a' a'*, Fig. 2, into two equal parts giving the entire system its stability when it is in movement. The said parts are appropriately spaced to permit of the unimpeded movement of the navigator, who takes his place upon the platform *h*, and at the same time protect him from the force of the air.

This aerial machine is steered by a rudder *i* arranged at the rear part in line with the reinforced beam.

The motor, which may be of any appropriate design, is fixed at *j* on the platform *h*. The screws *k k'* move in a plane perpendicular to the median plane of the apparatus, and are supported by arms composed of aluminium tubes at the extremities of which the bearings for the shaft *m* of the said screws are situated; these screws being beneath the horizontal plane, which in advancing compresses the air on which it rests and gives the maximum effect to the said propellers, receive the movement from the motor by means of chains, *l* and *l'*, and pinions keyed upon the motor shaft and on the shafts driving the screws; the chain *l'* is crossed by means of a small pulley in such a manner as to cause one of the screws to turn in one direction, while the other screw rotates in the opposite direction, thereby maintaining the equilibrium of the apparatus.

The navigator is able to enter the apparatus between the silk screens *n n'* through an opening *o* formed in one of these walls. From his post, the navigator is able to operate the movable part *b* by means of a lever and two cables *p q*; these cables are fixed to a part *r* which assumes a position in the navigating station corresponding to that occupied by the part *b*.

The part *b'* is simply operated by a cable *s* passing over the guide pulleys *t u v x*, and attached to each of the extremities of the said part. The cable *s* is provided at the

part s' passing through the navigating station with an indicator and an operating member of any appropriate kind. Finally the apparatus may rest on the ground by means of 5 four wheels y solid with the reinforced beam. The plane a and the platform h then form a certain angle with the horizontal, the front extremity of the aeroplane being higher from the ground than the rear extremity.

10 When the motor is started, the movement imparted to the screws causes the apparatus to advance. As soon as the forward movement attains a sufficient velocity, the horizontal plane a forming a given angle with the 15 line of travel compresses the air which lifts the apparatus from the ground.

In the course of the ascent, if there is a tendency for the equilibrium of the apparatus to be destroyed, and the plane a inclines 20 towards the side a' for example, it will be understood that as the side a' rises by a corresponding amount, the air compressed in the angle e escapes, while the angle g continues to store up air. The equilibrium of the apparatus is speedily reestablished. The same 25 thing would happen if the apparatus should become inclined towards the other side.

It will of course be understood that during 30 all these maneuvers, the movable parts b and b' are horizontal. If for any reason, such as injury to the motor for example, the apparatus should be obliged to stop, it is only necessary to bring the movable parts b b' into 35 the vertical position by means of the operating devices already described. The plane a

being closed at its extremities, and as it was already closed at its edges by the curved parts a' and a'' , it forms a parachute permitting of a safe descent. The movable parts b b' likewise serve to regulate the ascent and 40 descent of the apparatus.

For descending the part b' is brought into the oblique position determined by the inclination that it is desired to cause the apparatus to assume. 45

In order to rise in an oblique plane the part b is raised slightly while leaving the part b' in the horizontal position.

As a constructional detail it must be pointed out that the screens n and n' are 50 interrupted in the neighborhood of the motor in order to facilitate the circulation of the air for the cooling of the cylinder or cylinders.

Claim:

In an aeroplane, an oblong horizontal 55 plane having its side edges bent below the horizontal, a part b b' hinged to each end of the horizontal plane, a vertical plane below the horizontal plane and following the longitudinal axis thereof, said vertical plane having a portion extending above the horizontal plane, a rudder, screws and means for driving the screws. 60

In testimony whereof I have signed this specification in the presence of two sub- 65 ing witnesses.

MELVIN VANIMAN.
